No. 746,923.

PATENTED DEC. 15, 1903.

J. H. CLARK.
STOVE ATTACHMENT.
APPLICATION FILED FEB. 17, 1903.

NO MODEL.

UNITED STATES PATENT OFFICE.

JAMES H. CLARK, OF PORTAGE, WISCONSIN, ASSIGNOR TO THE JAMES H. CLARK COMPANY, OF PORTAGE, WISCONSIN, A CORPORATION OF WISCONSIN.

STOVE ATTACHMENT.

SPECIFICATION forming part of Letters Patent No. 746,923, dated December 15, 1903.

Application filed February 17, 1903. Serial No. 143,838. (No model.)

To all whom it may concern:

Be it known that I, JAMES H. CLARK, a citizen of the United States, residing at Portage, in the county of Columbia and State of Wisconsin, have invented certain new and useful Improvements in Stove Attachments; and I do hereby declare the following to be a full, clear, and exact description of the invention, such as will enable others skilled in the art to 10 which it appertains to make and use the same.

My invention relates to certain improvements in attachments for stoves, furnaces, &c., designed more particularly for promoting combustion, it also being adapted to provide for inducing increased draft whereby economy of fuel is obtained and increased heating capacity secured.

Said invention consists more especially of means adapted to be adjusted for changing 20 the direction of the products of combustion as relates to the combustion-chamber and the smoke-exit and of certain details of construction, combination, and arrangement of parts, substantially as hereinafter more fully disclosed, and specifically pointed out by the 25 claims.

In the accompanying drawings, illustrating the preferred embodiment of my invention, wherein is shown an ordinary heating-stove, 30 Figure 1 is a side elevation thereof with my improvement applied thereto. Fig. 2 is a broken detached view with the parts in position for effecting the return of the products of combustion to the fire-pot. Fig. 3 is a view 35 showing the parts permitting the escape of said products directly into the smoke-exit. Fig. 4 is a view in cross-section looking downward, taken on line *x*-*x* of Fig. 1.

It will be understood that I do not limit myself herein to details, as they may be changed as circumstances suggest without departing from the spirit of my invention and said invention still remain intact and be protected.

In carrying out my invention I preferably 45 employ a drum 1, superposed with relation to the stove, connection between which drum and stove being effected by, preferably, a short pipe-section 2, connected therewith in the usual manner, said drum connecting directly at its upper end with the smoke-exit 3. Within said drum is arranged an angular or

diagonal pipe 4, with its lower vertical portion extending down through the bottom of said drum externally of the stove and connecting at its lower end with the ash-pit in a 55 plane below the combustion-chamber, said portion extending well under the fire-grate. Said angular pipe has its upper end provided with an upwardly-flared portion or terminal 4^a, stopping about in a plane a little below 60 the upper convergent portion of the drum 1, the purpose of which will be presently apparent. A draft-pipe 5 has its vertical portion arranged to extend downwardly and terminating within a short distance of the floor 65 or otherwise adapted to receive cold air and suitably provided with a hand-actuated damper. Said pipe has connected to its upper end an elbow or return pipe-section 5^a, passing through the smoke-exit and depending within 70 said smoke-exit to a point within the flared upper end portion or terminal of the angular or diagonal pipe 4 to provide for delivering air-currents into said angular pipe. Slipped upon said depending portion of said return 75 pipe-section 5^a is a sliding pipe-section 6, with its lower end provided with a conical terminal portion 6^a, adapted to enter or engage the flared portion 4^a of the angular pipe 4, with 80 its upper edge or flared portion provided with a reversed flared annular flange 6^b, adapted to be engaged with the upper edge of said flared terminal portion 4^a or the top portion of the drum 1, the purpose of which will be presently explained. Said sliding pipe-section 85 is adapted to be moved in effecting such adjustment preferably by means of a combined pawl and lever 7^a, said lever having its forked portion suitably connected to said sliding pipe-section and pivoted at a convenient point upon or to a fixture attached to 90 said drum, said pawl 7^a being pivoted at its angle to said lever, with its actuating end adapted to be conveniently grasped by the operator with the operation of said lever, the 95 toothed portion of said pawl engaging a ratchet 7^b, which may constitute the support for the fulcrum of said lever.

It will be noted that with the conical terminal of the sliding pipe-section 6 in the position indicated in Fig. 3 the products of combustion will pass directly out through the 100

smoke-exit and that by adjusting said sliding pipe-section with the flange 6^b of its conical portion 6^a in the position indicated in Fig. 2 the course of the products of combustion will 5 be reversed, returning through the angular pipe-section 4 and its extension 4^a to the ash-pit below the fire-grate and up into the combustion-chamber, thus effecting further utilization of said products of combustion. Also 10 it will be noted that draft will be induced through the pipe 5 down through its return portion or elbow or return-section 5^a, through the angular pipe 4, and through the pipe extension of said angular pipe into the ash-pit 15 and up through the fire-grate, which draft can be readily regulated by the damper in said draft-pipe, as may be required. It will be seen that the heating capacity of the stove can thus be augmented when increased heat 20 is required and that by directing the passage of the products of combustion out through the smoke-exit the heating action thereof can be lessened, while by the use of the drum containing the principal features of my in- 25 vention the heating action is also increased. Also it will be observed that the products of combustion are thoroughly utilized by the tortuous route they are caused to travel through the drum, angular pipe, &c., and 30 back into the combustion-chamber previous to delivery, while the draft supplied to the stove may be varied according to the requirements of the case.

Having thus described my invention, what 35 I claim as new, and desire to secure by Letters Patent, is—

1. In an attachment of the character described, a drum adapted to be applied to a heater or fuel-burner, a pipe-section adapted 40 to return the products of combustion to said heater or fuel-burner, a sliding pipe-section having a terminal adapted to engage the outlet end of said pipe-section and said drum at its upper end, and means for actuating said 45 sliding pipe-section.

2. In an attachment of the character described, a drum adapted to be applied to a heater or fuel-burner, inclosing an angular pipe-section adapted to return the products 50 of combustion to said heater or fuel-burner having pipe connection with said heater or fuel-burner, a sliding pipe-section having a conical terminal adapted to engage the outlet end of said angular pipe-section and said 55 drum at its upper end, and means for actuating said sliding pipe-section.

3. In an attachment of the character described, a drum adapted to be applied to a heater or fuel-burner having a conical upper 60 portion connecting with the smoke-exit, an angular pipe-section arranged within said drum and having pipe connection with said heater or fuel-burner, and its upper end connecting with the upper part of said drum, 65 and a sliding pipe-section having a conical terminal adapted to engage the outlet end of said angular pipe-section and provided with

an annular flared flange at its upper edge adapted to engage said conical portion of said drum.

4. In an attachment of the character described, a drum adapted to be applied to a heater or fuel-burner, an angular pipe-section arranged within said drum having pipe attachment with said heater or fuel-burner, 75 below the fire-grate, and provided at its upper end with a flared terminal portion, a sliding pipe-section having a lower conical portion adapted to engage said flared outlet end of said angular pipe-section, and provided 80 with an annular flared flange at its upper edge, adapted to engage said drum at its upper end, and means for effecting the movement or adjustment of said sliding pipe-section.

5. In an attachment of the character described, a drum adapted to be applied to a heater or fuel-burner having an upper conical portion connected to the smoke-exit and having at its lower end, laterally of its center, means for effecting pipe connection with 90 said heater or fuel-burner, an angular pipe-section arranged within said drum, having a downward pipe extension for connection with said heater or fuel-burner, below the fire-grate, the upper end of said angular pipe-section having a flared outlet, a return pipe-section depending within said drum, a sliding pipe-section arranged upon said return pipe-section, provided with a conical terminal at its lower end adapted to engage said 95 flared outlet of said angular pipe-section, and means for actuating said sliding pipe-section.

6. In an attachment of the character described, a drum adapted to be applied to a heater or fuel-burner, having its upper conical portion connected to the smoke-exit and having at its lower end, laterally of its center, pipe connection with said heater or fuel-burner, a draft-pipe arranged externally 105 of said drum and having an elbow or return 110 pipe-section depending within said drum, a sliding pipe-section arranged upon said return pipe-section and having a conical terminal at its lower end, means for actuating said 115 sliding pipe-section, an angular pipe-section 120 arranged within said drum, having an upper flared outlet adapted to receive said conical terminal of said sliding pipe-section, said sliding pipe-section also having an annular flared flange adapted to engage the upper 125 portion of said drum, said angular pipe-section having pipe connection with said heater 130 or fuel-burner, below the fire-grate.

7. In an attachment of the character described, a drum having at its lower end, laterally of the center, pipe connection with a heater or fuel-burner, the upper end of said drum having a conical extension connected to the smoke-exit pipe, a draft-pipe arranged externally of said drum and having 125 a return pipe-section extending into said smoke-exit pipe, with its depending portion entering said drum, a sliding pipe-section 130 arranged upon said depending portion of said

return pipe-section, means for adjusting or moving said sliding pipe-section, comprising a lever having a pawl, an angular pipe-section arranged within said drum having at its upper end a flared outlet adapted to receive the conical terminal of said sliding pipe-section, said conical terminal having an annular flared flange at its upper edge adapted to engage the upper edge of said drum, said angular pipe-section having pipe connection with said heater or fuel-burner, below the fire-grate.

8. In an attachment of the character described, a drum adapted to be applied to a heater or fuel-burner, and containing an angular pipe-section adapted to return the prod-

ucts of combustion to said heater or fuel-burner, a sliding pipe-section adapted to engage the outlet end of said angular pipe-section, and means for actuating said sliding pipe-section, comprising a lever having its forked end provided with slots adapted to receive lateral pins from said sliding pipe-section, said lever having means for its retention at the desired point of adjustment.

In testimony whereof I affix my signature in presence of two witnesses.

JAMES H. CLARK.
